DESIGN FOR A GOLF CLUB

Joseph Sylvester, Hollis, N. Y.

Application March 27, 1937, Serial No. 68,441

Term of patent 7 years

To all whom it may concern:

Be it known that I, Joseph Sylvester, a citizen of the United States of America, residing in Hollis, Long Island, county of Queens, and State of New York, have invented a new, original, and ornamental Design for a Golf Club, of which the following is a specification, reference being had to the accompanying drawing, forming part thereof.

The figure of the drawing is a front perspective view of a golf club showing my new design.

The dominant feature of my design resides in the portion shown in solid lines and particularly the upper part thereof.

I claim:

The ornamental design for a golf club substantially as shown and described.

JOSEPH SYLVESTER.
